CLAIM

The ornamental design for a hand-held computing/controller device, as shown and described.

DESCRIPTION

FIG. 1 is a perspective view illustrating a hand-held computing/controller device in accordance with the present invention;

FIGS. 2 and 3 are top and bottom views respectively thereof;

FIGS. 4 and 5 are side views respectively thereof;

FIGS. 6 and 7 are end views respectively thereof;

FIGS. 8, 9 and 10 illustrate perspective, top and end views respectively of another embodiment thereof; and,

FIG. 11 is a perspective view of another embodiment thereof.
